GENERATOR TYPE BURNER AND FUEL TANK

James L. Breese, Santa Fe, N. Mex., assignor, by
mesne assignments, to Breese Burners, Inc.,
Santa Fe, N. Mex., a corporation of Delaware

Application January 13, 1944, Serial No. 518,046

4 Claims. (Cl. 158—91)

1

My invention relates to an improvement in liquid fuel burners and is particularly applicable to a generator type of liquid fuel burner in which a liquid fuel supply is vaporized by the heat of a local initial combustion and the vaporized fuel is delivered to a pot type burner.

One purpose is to provide improved means for storing a relatively large mass of liquid fuel adjacent the burner.

Another purpose is to provide improved means for insulating most of said mass of fuel from the heat of the initial combustion.

Another purpose is to provide improved means for delivering liquid fuel to the zone or area of initial combustion.

Other purposes will appear from time to time throughout the specification and claims.

My invention is illustrated more or less diagrammatically in the accompanying drawings, wherein—

Figure 1 is a vertical axial section;

Figure 2 is a section along the line 2—2 of Figure 1;

Figure 3 is a vertical axial section through a variant form of the device.

Like parts are indicated by like characters throughout the specification and drawings.

Referring first to the form of Figures 1 and 2, I generally indicates an outer housing or container wall having an annular bottom wall 2, and a top wall 3. 4, 4 are any suitable spacing supports for spacing the bottom wall upwardly from any suitable supporting surface or floor 5. 6 is an inner cylindrical wall which extends upwardly from the inner edge of the bottom annulus 2 and abuts against the top member 3.

An inner vaporizing chamber is defined by the cylindrical outer wall 1, the bottom wall 8 and the central portion 3a of the top wall 3. The space between the walls 6 and 7 is downwardly open. The cylindrical walls 6 and 1 may be spaced apart at their lower edge by strips 7a. Air may circulate through the apertures 9 in the top wall 3, and between the walls 6 and 7. 10 is any suitable filling sleeve in the top wall 3 which may be closed by the removable cap 11, shown as including the screw threaded downwardly extending portion 12. The walls 1, 2, 3, and 6 thus define an annular outer container which is separated, by the air space between the walls 6 and 7, from the inner container within the wall 7. Liquid fuel may pass from the outer to the inner container along the duct 13 which is shown as having a closed end 14 and a liquid admission aperture 15, through which liquid may flow to the interior

2

of the inner chamber. 16 is a heat responsive member herein shown as a warping bar which, when the fuel level is low, as shown in Figure 1, takes the open position in which it is shown in that figure. Fuel then flows in, and as the fuel level rises, the bar is cooled, and moves toward the closing position, in such fashion that the flow of fuel from the outer container to the inner container may be cut off.

Air is admitted to the inner container by the following means: 18 indicates a fixed tube extending downwardly from the cover 3a to a level close to the bottom of the interior of the container. The tube 18 is shown as provided with a plurality of slots 19 which may, if desired, be diametrically opposed. For strengthening purposes, I may use connecting metal parts 20. 21 indicates an open topped inner tube which may be rotated by the handle member 22, the handle member also serving to limit the downward movement of the tube 21 into the tube 18. The tube 21 is provided with slots 23 arranged in any suitable relation to the slots 19 in such fashion that rotation of the inner tube 21 by the handle 22 has a shuttering or valving effect. It will be understood that the slots are preferably so arranged that by rotation of the tube 21 through a predetermined arc, the air passage space controlled by the slots may vary from zero to a predetermined maximum. Thus a readily controllable air supply for the interior of the inner or generator chamber is provided.

25 indicates a neck or tube upwardly extending from the inner top portion 3a. Mounted upon its upper end is a pot 26 herein shown as having a circumferential side wall 27, a bottom 28 and an upper outwardly extending flange 29 with a downwardly turned outer portion 30. The pot is provided with a plurality of primary air inlet apertures 31 extending circumferentially about the wall 27 and arranged at varying distances from the pot bottom. 32 indicates a single top row of secondary air inlet apertures extending about the wall 27 adjacent the open top of the pot. The otherwise open top of the pot is partially closed by the centrally apertured flame ring 33 which may be secured by screws or other suitable means 34 to the flange 29. Secured to the flange portion 30 is an outer sleeve 35 herein shown as having a bottom 36 provided with a large central aperture 37 through which air may flow into the space between the member 35 and the pot wall 27.

Referring to the form of Figure 3, I illustrate a substantially identical pot 26 and an outer housing 35 mounted on the upwardly extending neck

or tube 25. However, I employ a single fuel chamber defined by the top wall 3 and the circumferential side wall 1 and the closed bottom wall 2a. Instead of having an entirely separate inner generating chamber, I define an inner generator space by providing two circumferential inner walls 40, 41 which between them define a dead air space. They may be made as a single member connected by an upper flange 42 riveted or otherwise secured as at 43, to the top member 3. The space between the partitions 40 and 41 is open at the bottom as at 44 and the liquid fuel level may be located slightly above the lower edges as at 45. However, the mass of the liquid fuel between the walls 1 and 40 will be to a substantial extent insulated from the generator chamber defined by the wall 41. The air admission means are shown as identical with those indicated in Figure 1.

It will be realized that whereas I have shown and described an operative device, still many changes might be made in the size, shape, number, arrangement and disposition of parts without departing materially from the spirit of my invention. I therefore wish that my showing be taken as in a large sense diagrammatic and illustrative, rather than limiting me to the precise showing.

It will be understood in particular that the size, shape and proportion of the fuel storage and generator chambers may be widely varied and that, if desired, the neck or tube 25 may be sufficiently offset from center to permit ready upward removal of the inner air tube 21.

The use and operation of my invention are as follows:

Combustion may be initiated in the generator or vaporizing chamber by dropping a match or ignited waste either down through the central tube 25 or down through the open topped inner tube 21. The tube is so set as to supply sufficient air to support combustion and combustion will take place, at the top level of the fuel, to a sufficient degree to initiate vaporization of the fuel. Vaporized fuel, with some additional air supply, will then flow upwardly through the tube 25 and into the interior of the pot 26 and will there receive the primary air supply through the apertures 31. As the mixture of primary air and vaporized fuel rises in the pot 26, it receives a final air supply through the secondary air inlet 32 and the final mixture burns at the top of the pot, substantially at the level of the secondary air inlets 32 and the flame flows upwardly through the central aperture of the flame ring 33. It will be understood that any suitable combustion chamber, heater, stove, or radiating member may be employed. It will also be understood that the tube 25, which is shown as extending vertically from the vaporizing chamber may be bent to extend laterally, in such fashion that the axis of the pot may be horizontal or otherwise be inclined from the vertical. I do not illustrate any such variation, however, as the present invention is directed primarily to the means for storing and feeding and insulating the liquid fuel.

I illustrate in the drawings herein a generator type burner which includes in a compact unit the three main elements of a fuel storage tank, a vaporizing chamber, and a mixing and burning pot which may be employed in connection with any suitable burner or heater not herein shown. The type of burner described herein employs a substantial mass of fuel which is stored in the outer housing within the wall 1 and which ren-

ders it unnecessary to employ a fuel transmitting pipe permanently connected to the assembly. The level of the fuel is at all times below the level of the pot or burner. The oil is raised into the burner for mixing and combustion by converting it into a gas or vapor. This gas or vapor may rise and flow by its own thermal expansion, or it may be drawn upwardly to the burner by natural draft, if any suitable combustion chamber with attached flue is employed. If desired, any suitable blower or fan means, not herein shown, may be employed for forcing the vaporized fuel upwardly to the burner. The fuel level in the vaporizing chamber varies, but it is not the level of the fuel or the mass of the fuel which determines the rate of combustion. Regardless of variations in level, in the generator chamber, the amount of fuel burned is controlled by the amount of air admitted through the air inlet pipe 21. Whereas I illustrate the inflow of air as controlled manually, it will be understood that any suitable thermal control means may be employed. It may be advantageous, for starting, to employ a wide open air inlet passage. It must be kept in mind that there must be some air flow at all times into the vaporizing chamber, if continuous operation is to be maintained, since the only means for getting fuel into the pot 26 is to convert it into a gas or vapor. Enough air must be admitted to obtain the combustion necessary for vaporization of the gas. The more air which is admitted, the greater the rate of combustion.

The air admitted through the slot or slots 19 and 23 will be admitted in sufficient quantity not merely to maintain the combustion necessary for the vaporization of fuel from the surface of the fuel within the vaporizing chamber, but also to provide an excess supply of oxygen. It is essential not merely to maintain a vaporizing flame in the vaporizing zone within the vaporizing chamber but also to carry some flame and unburned oxygen up into the pot so that when the additional supply of oxygen is provided through the apertures 31 and 32, combustion will take place. In effect, ignition of the final mixture may take place from the tip of flame extending upwardly or outwardly from the vaporizing zone into the mixing zone. The vaporizing flame serves to vaporize the liquid hydrocarbon. As a matter of fact for convenience in the present application, the mixing zone or pot 26 is shown as directly above the vaporizing chamber defined by the walls 1 or 41. It will be understood, of course, that this relationship may be altered.

I find it convenient to employ a burner pot of the type heretofore used in hydroxylating burners as shown in earlier patents of my own. The vaporized hydrocarbon flows from the vaporizing or generating zone to the mixing zone and there receives sufficient additional oxygen to form a final mixture. This mixture burns in or above the mixing zone or the interior of the pot. At the lower stages of air supply, combustion may also take place in the pot proper. At the higher stages of combustion as where a maximum supply of air is admitted through the pipe 21, the flame will extend well up into the interior of whatever heater or combustion chamber is employed.

It will be understood that considerable heat may be generated in the vaporizing chamber. I therefore find it desirable to insulate a substantial part of the liquid fuel supply from such

heat. I provide an air circulating space between the walls 6 and 7 of Figure 1, or the dead air space between the walls 40 and 41 of Figure 3.

In the form of Figure 1, I provide the further feature of controlling the flow of liquid fuel to the vaporizing chamber in response to variations in heat conditions in the vaporizing chamber. As an example of such means, I illustrate the warping bar 16 which serves as a valve closure for the aperture 15, effective to cut off liquid flow from the outer chamber to the vaporizing chamber, when there is a maximum depth of liquid in that chamber. It will also be noticed that the outer chamber is further removed from the pot than is the vaporizing chamber. Outside air flowing upwardly through the aperture 37 and about and into the pot 26 produces a curtain of moving air which serves to some extent as an insulating medium. This, in connection with the air gap between the outer sleeve 35 and the top of the outer chamber, and in further connection with the air space between the top of the fuel and the top wall 3, prevents overheating of the fuel in the outer chamber by the heat of combustion in or above the pot.

I claim:

1. In a liquid fuel burner assembly, a burner having a partly closed bottom, a tank having circumferentially extending side walls, a bottom wall and a top wall, partition means in said tank segregating part of the interior of the tank from the rest of the tank, the segregated portion of the tank constituting a liquid fuel vaporization chamber, the rest of the tank interior constituting a liquid fuel storage chamber, a duct connecting the vaporizing chamber and the storage chamber, a duct extending upwardly from the top wall of the tank and in communication with the interior of the liquid fuel vaporization chamber, said burner being mounted on said duct, the interior of said duct being in communication with the interior of said burner through the partly closed bottom of the burner, and means for admitting a variable controllable air supply, to the interior of said vaporization chamber, adequate to support vaporizing combustion.

2. The structure of claim 1 characterized by and including the employment, as partition means in said tank, of a double wall defining an air space circumferentially surrounding said liquid fuel vaporizing chamber.

3. The structure of claim 1 characterized by and including the employment, as partition means in said tank, of a double wall defining an air space circumferentially surrounding said liquid fuel vaporizing chamber, the upper and lower walls of said tank being apertured in alignment with the interior of said double wall, whereby air is permitted to circulate freely between said fuel vaporization chamber and said liquid fuel storage chamber.

4. The structure of claim 1 characterized by and including said duct terminating below the normal level of fuel in said vaporization chamber, and heat responsive means, normally submerged in the liquid fuel in said vaporization chamber, adapted to control the flow of liquid fuel from said storage chamber to said vaporization chamber.
